Primary Examiner — Eric L Goodman*Assistant Examiner* — Lee D. Starr(74) *Attorney, Agent, or Firm* — Katten Muchin Rosenman LLP(57) **CLAIM**

We claim, the ornamental design for an inhaler, as shown and described.

DESCRIPTION

FIG. 1 is a left side perspective view of an inhaler, showing our new design;

FIG. 2 is a right side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a left side perspective view thereof in an open configuration;

FIG. 10 is a right side perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

Where portions shown in broken lines form no part of the claimed design.

1 Claim, 12 Drawing Sheets(56)
